UNITED STATES PATENT OFFICE

106,957

DESIGN FOR A TABLE

Archie H. Bechtol, Daytona Beach, Fla.

Application September 20, 1937, Serial No. 71,692

Term of patent 3½ years

To all whom it may concern:

Be it known that I, Archie H. Bechtol, a citizen of the United States and a resident of Daytona Beach, in the county of Volusia, and State of Florida, have invented a new, original, and ornamental Design for a Table, of which the following is a specification, reference being had to the accompanying drawing, forming a part thereof, and in which:

Fig. 1 is a front perspective view of the table, showing my design with the front drawers thereof extended;

Fig. 2 is a rear perspective view of the table, on a reduced scale with the drawers thereof in normal closed position and as seen from line 2—2 in Fig. 1; and

Fig. 3 is a side elevational view of the same as seen from line 3—3 in Fig. 2.

I claim:

The ornamental design for a table, as shown.

ARCHIE H. BECHTOL.
